DESIGN FOR A CAN OPENER

Alfred M. Jacobson, Houston, Tex.

Application December 8, 1944, Serial No. 116,801

Term of patent 14 years

(Cl. D22—2)

To all whom it may concern:

Be it known that I, Alfred M. Jacobson, a citizen of the United States, residing in the city of Houston and county of Harris and State of Texas, have invented a new, original, and ornamental Design for a Can Opener, of which the following is a specification, reference being had to the accompanying drawing, forming a part thereof.

Figure 1 is a side elevational view of a can opener, showing my new design;

Figure 2 indicates an end elevational view; Figure 3 is the reverse end elevational view shown thereof; and

Figure 4 illustrates the lower end view of the design features outlined in elevation.

I claim:

The ornamental design for a can opener, substantially as shown.

ALFRED M. JACOBSON.
